Attorney.

UNITED STATES PATENT OFFICE.

SAMUEL A. NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

PROCESS OF MAKING LITHOGRAPHIC PLATES.

1,245,119.

Specification of Letters Patent. Patented Oct. 30, 1917.

Application filed August 11, 1914. Serial No. 856,201.

To all whom it may concern:

Be it known that I, SAMUEL A. NEIDICH, a citizen of the United States, residing at Edgewater Park, in the county of Burlington and State of New Jersey, have invented a certain new and useful Improvement in Processes of Making Lithographic Plates, of which the following is a full, clear, and exact description, reference being had to 10 the accompanying drawings.

This invention relates to a process for the preparation of a metal lithographic plate, the object being to reduce the expense, time and skill required in the preparation of a 15 plate for printing, as well as to produce a more durable plate and one having other desirable properties hereinafter mentioned. In the ordinary process of preparing metal lithographic plates, a grained plate has the 20 work or image applied direct to it in some greasy medium and thereafter the balance of the plate is etched and gummed to make it ink-resisting when moist.

In the old processes it is very important 25 that no grease be present on the grained plate where printing is not desired, and that the plate be kept free from oxidation, and great skill is required as well as considerable time in accomplishing the etching. Inasmuch as the etching operation tends to remove the work, the usual method has been to partially etch the plate and thereafter strengthen the work and then further etch the plate and further strengthen the work, 30 if necessary. These successive operations require great skill and caution, lest the work be partially removed by the etching substances. There is great liability of spoiling the plate during this process, for 35 if the etching removes the least part of the work, the plate is ruined, or is only preserved by tedious subsequent operations. Unless the operation is carried out with the greatest possible care, the plate lacks durability, as the image is liable to become partially removed during the operation of the 40 printing.

I have found that while a plate thoroughly etched is incapable of receiving ink 45 when moist, it is capable of having wax images firmly affixed by action of heat. This process relates particularly to reproduction of work of the character of typewriting or matter already existing in the form of type 50 matter, zinc cuts and the like, and consists

primarily in locally depositing where the image is desired, a hard wax, or compound of hard waxes, and heating them to affix work to the plate.

In order to carry out this process as affecting the duplication of typewriting lithographically, I thoroughly etch the entire surface of a grained plate in the ordinary lithographic manner. I prepare a sheet of carbon paper containing a maximum percentage of hard wax consistent with its giving off a portion of its surface under the blows of the typewriter to the zinc plate. One of my etched plates, from which any soluble gum has been dissolved, 60 is now covered with a sheet of this carbon paper and the two inserted in an ordinary typewriting machine, and the necessary matter typewritten through the carbon onto the zinc plate. I have found by experience 65 that a carbon ink of this character when locally deposited on the plate and heated, will become thoroughly fixed to the pre-etched surface and capable of being proceeded with in the ordinary lithographic 70 method without subsequent treatment of any kind.

In order to reduce the tendency of the molten wax to spread the work, I incorporate in the carbon ink a maximum percentage of pigment for the purpose of making the compound as viscous as possible when molten. While no other step is necessary for the production of a typewritten lithographic plate, I prefer after depositing the 75 copy on the zinc plate, to coat it with gum and dry the gum, previous to heating, as this overcomes the tendency of typewritten work to spread by the flow of the wax.

In the reproduction of lithographic matter already existing in the shape of type, zinc cuts or other relief printing surfaces, I find it is only necessary to coat the printing surface of the type or other form with a solution of hard wax, preferably carnauba 80 in one of its well-known solvents, as benzol, allowing the solution to evaporate and thus depositing a very thin film of wax, on the type surface. The type surface is then brought into contact with a warm plate and 85 the wax thereby melted, firmly attaches to the pre-etched plate, forming the image for the lithographic work. In this case, the film is so thin that no spreading occurs.

For the production of work from a photo- 90

graphic negative I prefer to take a hard wax transfer by ordinary photographic means, the same being impressed on the warm plate. It is a vital characteristic of 5 all of the various operations above described, that there is deposited on the pre-etched plate, a molten hard wax in the absence of gum.

The drawings further illustrate my process: in which Figure 1 is a cross section very 10 much enlarged, of an ordinary grained metal plate; Fig. 2 is a cross section of such plate after the entire face thereof has been etched; Fig. 3 is a cross section after the work is 15 applied, and Fig. 4 is a plan of a portion of the plate shown in Fig. 3.

In Figs. 1 to 3, A represents the body of the metal plate and a the grained surface thereof; B represents the coating formed by 20 the action of the etching materials on the zinc which is a substance capable when moist, of rejecting ink. This etching is shown graphically as higher than the grain, though in reality it is incorporated with it. 25 E, in Figs. 3 and 4 indicates the image which is applied to the etched surface of the plate in the form of a hard waxy resisting material, which by heating becomes homogeneous and firmly attached to the etched plate.

30 In the above description it is to be understood that the word "etched" is used in the commonly accepted lithographic meaning of the word, to cover any means of making surfaces ink-resisting when moist, and not 35 in the ordinary sense of the word, as meaning cutting away of the metal by an acid. The word "work" is used throughout to mean the image which is to receive the ink and be duplicated in the printing process.

40 The process described refers more particularly to the production of a plate for the reproduction of work of the character of typewriting, type matter, zinc cuts and other work already existing, though my pre-45 etched plate is adapted to receive work by other means, such as autographic work, line drawings, artist sketches, and the reproduction of such work is covered in a copending application of mine, No. 856,202, filed August 11, 1914. The pre-etched plate itself,

ready to receive work, forms the subject matter of my Patent 1,203,770, issued Nov. 7, 1916.

Having thus described my invention, what I claim is:

1. The process of preparing a metallic lithographic plate consisting of etching the entire face of the plate and applying directly to the etched surface the image in the form of a hard waxy substance capable of 60 being attached to the pre-etched plate by heat.

2. The process of preparing lithographic plate consisting of etching the entire face of the plate, removing any soluble gum 65 from such face, and applying directly to the etched surface the image in the form of a hard waxy substance capable of being attached to the pre-etched plate by heat.

3. A process of preparing a lithographic 70 plate consisting of etching the face of the plate, placing on such etched face a hard waxy substance defining the image and heating the waxy substance to affix such image.

4. The process of preparing a lithographic 75 plate consisting of etching the entire face of the plate, depositing the work locally in a hard waxy substance, coating the plate with soluble gum and subsequently heating the plate.

5. The process of preparing a lithographic plate consisting of etching the entire face of the plate and causing a heated waxy image to adhere to the plate.

6. The process of preparing a lithographic 85 plate consisting in etching the face of the plate and thereafter causing a waxy image to be fixed to the etched surface by heat.

7. The process of preparing a lithographic plate consisting of etching the face of the 90 plate, transferring to the etched surface a design formed of carnauba wax or its equivalent, said design being affixed to the plate by heat.

In testimony whereof, I hereunto affix my 95 signature in the presence of two witnesses.

SAMUEL A. NEIDICH.
